FINNED TUBE AND METHOD FOR FORMING
THE SAME

Elmer E. Ledbetter, Dearborn, Mich.

Application October 7, 1935, Serial No. 43,941

5 Claims. (Cl. 113—118)

The invention relates to finned tubes such as used in radiators of various types, for the absorption or dissipation of heat. It is the object of the invention to obtain a simple construction and method of manufacture of the same, having among other advantages, first, that it permits of making the tubes and the fins of dissimilar metals; second, that it forms a very effective means for heat transfer; third, that it securely connects the fins to the tubes, and fourth, that it lends itself to manufacture and assembly by automatic machines. With these objects in view the invention consists in the construction and method as hereinafter set forth.

15 In the drawing:

Figure 1 is a side elevation of one of the fins;
Figure 2 is an edge elevation thereof;

Figure 3 is a perspective view illustrating the manner of securing the fins to the tubes;

20 Figure 4 is an enlarged section in the axial plane of the tube illustrating the attachment between the fins and the tubes;

Figure 5 is a side elevation of a portion of the completed structure;

25 Figure 6 is a view similar to Figure 4 showing a modified construction.

With radiators of the tube and fin type, efficiency in heat transfer is dependent upon the rate of conduction through the joint between the tube and fins and this in turn is dependent upon the extent of actual contact surface between these members. There is also the problem of mechanically mounting and securing the fins upon the tubes so as to permit of quick 30 assembly and to produce good contact in the joints. Still further, it is desirable to manufacture the fins with a minimum waste of metal. I have therefore devised a construction in which 35 separate split fins apertured to surround the tube and provided with laterally extending contact flanges are secured by a continuous strip wound spirally about these flanges and passing through the splits in the successive fins. By this means the flanges are pressed into firm contact with the outer surface of the tube so as to produce a high rate of heat conduction therebetween. The construction is also one which can be manufactured at low cost and which as above stated lends itself to assembly by automatic machines.

40 As illustrated, A are the fins which are cut from sheet metal with a central aperture B corresponding to the size of the tube and with a lateral flange C struck out to surround this aperture. In the forming of these fins they are split along a radial line D which also extends through

5 the flange C. The fins thus constructed are mounted upon a tube such as E, and the portion A' upon one side of the split in each fin is laterally deflected from the portion A² on the opposite side of the split, so as to come substantially into alignment with the corresponding portion A² of the adjacent fin. A strip G is then wound spirally around the tube E and flanges C passing through the spaces between the portions A', A², and so on continuously throughout the length 10 of the tube. This strip G constitutes a spacer between fins and also a binding means for clamping the flanges C against the outer face of the tube so as to obtain good contact. As specifically shown, the strip G is in the form of a channel 15 member, the web portion G' contacting with the flanges C and the side flanges G² of the strip lying adjacent to the fins. Thus in addition to the conduction between the tube and the flanges C heat is also transferred through the web G' and 20 flanges G² into the fins.

25 The method of assembly just described is one which could be performed manually but it is obvious that it is also one which might be performed by an automatic machine. However, the construction of such machine forms no part of the present invention.

30 In assembling the spacer strip G it may sometimes be found desirable to have the strip at an elevated temperature during the winding operation, thus causing a more intimate contact due to the shrinkage of the metal after the strip has cooled to the same temperature as the remainder of the structure. It is also within the purview of the invention to form a construction 35 in which the lateral flange C is wholly or partially omitted. In such case the spacing strip G will contact directly with the outer surface of the tube E as illustrated in Figure 6. In this figure the unflanged fins A³ are mounted on the tube E. The flanged spacing strip G is spirally wound 40 on the tube E contacting directly therewith. The flanges G² contact with the sides of the fins A³ thereby serving to conduct the heat from the tube to the fins.

45 It is also to be understood that the spacer strip G may be of any desirable cross section whereby it may be spirally wound around the tube intermediate the fins.

50 What I claim as my invention is:

1. The method of manufacturing finned tubes comprising the forming of a series of fins from sheet metal, each fin having a central aperture with a laterally extending flange surrounding the same and being split radially through both 55

fin and flange, mounting a series of fins upon the tube with the portions upon opposite sides of the split in each fin laterally deflected, and spirally winding a binding strip around said tube 5 and the laterally extending flanges of the fins, said strip being tensioned to press said flanges in firm contact with the outer surface of the tube and passing successively through the radial splits of one fin into engagement with an adjacent fin.

2. The combination with a tube, of a series of split sheet metal fins sleeved upon said tube, each fin being provided with a laterally extending annular split flange surrounding the tube and the portions of each flange on opposite sides of the strip being laterally deflected from each other and a binding strip of channel shaped cross section wound spirally about said tube and flanges to press the same into close contact therewith, the web portion of said strip contacting with said annular flanges and the flanges of the strip contacting with adjacent fins to form additional heat conducting means between said tube and fins.

3. The method of manufacturing finned articles comprising the forming of a series of radially split sheets centrally apertured and each provided with a laterally extending portion surrounding said aperture, mounting said sheets upon a core member with the portions upon opposite sides of the split in each sheet laterally deflected, spirally winding a binding strip around

said core member and laterally extending portions of the sheets, said strip passing successively through the spaces between deflected portions of said sheets and heating said binding strip prior to completion of the winding operation to increase the binding effect of said strip upon subsequent cooling. 5

4. A finned article comprising a core member, a series of radially split fins sleeved upon said core member, each fin having a laterally extending portion surrounding the core and the portions on opposite sides of the split being laterally deflected to form a space therebetween, and a spirally wound binding strip surrounding said core member and laterally extending portions of the fins 15 passing successively through the splits in each fin.

5. A finned article comprising a core member, a series of radially split sheets mounted on said core member, each sheet having a laterally extending annular split flange surrounding the core member, the portions on opposite sides of the split being laterally deflected to form a space therebetween, said sheets extending radially outward from said core member for a distance not 20 substantially less than the diameter of said core member and a spirally wound binding strip surrounding said core member and laterally extending portions of the sheets and passing successively through the splits in each sheet. 25
